UNITED STATES PATENT OFFICE.

HERMAN J. SCHULTZ, OF CHICAGO, ILLINOIS.

PRINTING PRESS AND LIKE MACHINE.

Application filed July 5, 1919. Serial No. 308,843.

To all whom it may concern:

Be it known that I, HERMAN J. SCHULTZ, a citizen of the United States, residing in the city of Chicago, county of Cook, and State of Illinois, have invented certain new and useful Improvements in Printing Presses and like Machines, of which the following is a specification.

This invention relates to improvements in printing presses and like machines and has for its object to provide means whereby sheets of paper or like material in advancing to the printing rolls are accurately positioned with relation thereto and in advancing past a selected point are subjected to guiding mechanism that will automatically act in case of imperfections in the margin of the sheets or when the sheet of paper or like material is feeding into the machine in imperfect alignment either by reason of the sheet being placed before or beyond the side guiding mechanism whereby the stopping action of the machine is actuated.

In the drawings:

Fig. 1 is a fragmentary side elevation of part of a printing press and automatic feeding mechanism showing the improved device applied thereto.

Fig. 2 is a plan view of part of the mechanism shown in Fig. 1, parts being omitted and other parts broken away for clearness of illustration.

Fig. 3 is an enlarged side elevation of the side guiding mechanism with the improvements applied thereto.

Fig. 4 is a detail view of the mechanism embodying my invention.

Fig. 5 is a sectional view taken on lines 5-5 of Fig. 4 and looking in the direction of the arrows.

Fig. 6 is a view similar to Fig. 4 but in different relative position of the several parts.

Fig. 7 is a detail of the detector with a sheet improperly fed entirely under the contacting arm.

Referring particularly to Figs. 1, 2 and 3 of the drawings, the frame 1 has mounted thereon an automatic paper feeder 2 which is of the type used with a flat bed two revolution cylinder press and to which the device embodying the invention is applied. 3 indicates one of the printing cylinders. The sheets of paper 4 are advanced successively over the sticks 5 and are subjected to the ac-

tion of the side guide mechanism 6. This side guide is of a well known type and comprises gripping shoes 7 pivotally mounted on an angle bar 8 which bar is pivoted at 9 to bracket arm 10 and has means for causing the shoes to engage the paper and adjust the paper sidewise of the machine. The bar is provided with spring 11 having one end fixed at 12 to the hub 13 of the angle bar and has its other end secured to a nut 14 having threaded engagement with the pivot pin 15. The action of spring 11 is to rock the angle bar on its pivot and cause the shoes to engage the margin of the paper sheet and hold it between the shoes and base plate 16 of the bracket 10.

The bracket 10 is adjustably secured at 17 to a clamp 18 mounted on the side guide operating shaft 19. The shaft 19 terminates in a rack extension 20 slidable in the bearing 21 in the standard 22. The side guide operating shaft is reciprocated by reason of the actuating of a segmental gear 23 on stub shaft 24 engaging the rack 20. This action is produced by the pull rod 25 secured to the cross head 26 on the outer end of the stub shaft 24. The upper angle arm 8^a of the angle bar 8 is provided with a seat 8^b to receive roller 27 on the arm 28 of a bell crank 29 pivoted at 30 to the bracket 10. A depending arm 31 of the bell crank 29 is caused to engage a lug 32 on the inward movement of the shaft 19 transversely of the travel of the paper sheet and thereby trip the angle bar and through the action of the spring 11 rock the angle bar downward bringing the shoes in contact with the margin of the paper and securely holding the paper between the shoes 7 and the base plate 16 of bracket 10. The spring 11 has just enough tension, when regulated, for heavy or light paper stock, so that the grippers merely shift the paper against the side lugs and then slip off. If tension is too great, the paper will cramp and the stock be mutilated. The sheet of paper will be carried transversely of its travel when shaft 19 moves outwardly by the mechanisms just described until the arm 31 of the bell crank engages the lug 33 which lug and also the lug 32 are secured to a bed plate 34 adjustably mounted on a bar 35 secured to the table 2^a of the automatic feed mechanism. At the point of contact of the bell crank arm 31 with the lug 33 (shown in Fig. 3), the paper will have moved to a

point where the margin thereof will be brought in contact with the side guide stops 36 and the gripping shoes will be disengaged therefrom and the sheet of paper will be advanced through the printing press in the usual and well known manner. The grippers remain in a closed position with the sheet firmly grasped until the latter edge of the sheet contacts the guide stops 36, as shown in Fig. 2, at which time the jaws are opened and the paper is released.

Referring to the bed plate 34 it will be noticed that the inner end or that next to the edge of the paper sheet projects beneath the path of travel of the incoming sheets of paper and is provided with an extended member 37. Upon the base member 37 are posts 38 and 39. A bar 40 is pivotally mounted at 41 to post 38 and projects toward the incoming sheets of paper and has a depending finger 42 which finger is above and slightly at one side of the margin of the paper when the paper is properly placed with relation to the side guide stops 36. The forward end of bar 40 passes through a slot 43 in the post 39 and is normally held upward by a lever 44 pivoted at 45 to a post 46 on the base 37, said lever having a spring 47 secured thereto and the spring having its other end secured at 48 to post 46 thereby causing an upward pull on the lever 44 and through contact of the lever 44 and bar 40 the latter is held up and in contact with a pin 49 secured to a locking latch member 50 pivoted at 51 to bar 40 the other end of which latch member is caused to engage the stop bar 52 secured to post 46. As shown in Figure 4, the latch lever 50 in its downward movement will contact the pin 50^a, inserted in the post 39 and having an end projecting into the space 43. The position of the pin 50^a is predetermined in order that it will not contact the latch member 50 during normal operation. When the finger 42 falls into the slot 61, the latch member 50 will contact the pin 50^a and will be tripped upward on its pivot 51, so that the latch member 50 will not intercept the hook portion 62 of lever 53.

50 A latch member 53 is pivotally secured at 54 to the post 46 and has a cam face projection 55 thereon adapted to contact the end 56 of lever 44. As shown in Fig. 1, the link 57 is secured at 58 to the latch 53 and has its other end pivotally secured to an arm 58^a which arm is fixed to a shaft 59 known as the kick-off shaft. The shaft 59 is rocked through the actuation of the pull rod 60 and its associated parts which are of a well known structure and form no part of this invention. In preventing the reciprocation of the pull rod 60, the detecting device functions the starting and stopping mechanism of the printing press to which it is attached not shown in the drawings, nor explained in

the specification. This starting and stopping mechanism of an ordinary printing press is not a part of the present invention and its only importance is that it is functioned by the operation of the detecting device when 70 it fails to contact with the edge of the paper sheet. All of the aforesaid mechanisms are assembled and are operated in timed relation to each other. It will be understood that as the shaft 59 is rocked the latch member 53 through its connections therewith will be rocked on its pivot and caused to travel forward and back carrying the cam faced projection thereof beneath the end of the lever 44 thereby rocking the lever on its pivot and releasing the other end of the lever from contact with the bar 40 thereby allowing the bar 40 by gravity to descend and in so doing bring the finger 42 of the bar 40 into contact with the margin of the paper 85 which contacts with the incoming paper or like material will cause the bar 40 to come to rest and be returned to its former position when the shaft 59 causes a return movement of the bar to its former position. While the shaft 59 is causing through the aforesaid connections therewith a vibratory action of the bar 40, the side guides are performing their functions whereby the sheets of paper or like material are brought to proper position against the stops 36. As the paper passes beneath the finger 42 of the bar 40, should a sheet through improper alignment from any cause or through failure of the side guides to perform their function not come within the vertical plane of action of the bar and finger or should the margin of material be mutilated the finger will fail to be stopped and will drop into the aperture 61 and in doing so will cause the bar 40 to fall below a point which will allow the return of the latch member 53 by reason of the tooth 62 on latch 53 engaging the bar 40, preventing oscillating motion thereby arresting the rocking of shaft 59 and in so doing causing through the usual means not shown a stoppage of the entire press mechanism. It will be readily understood that an overfeeding of the paper will produce a like result by reason of the projection 63 of the finger 42 contacting the paper and holding the oscillating arm 40 in a position where the pivotal latch 50 is engaged by the hook portion 62 of the swinging latch member 53, as shown in Fig. 7. That part of the latch member, which is engaged by this hook portion, is a notched projection on its lower edge which moves down into position by rotation of the latch upon its pivot 51. The actuation of the latch member being stopped in this manner has a like effect to the previous mode of stopping a machine, as explained where the paper is not contacted by the arm 40, as shown in Fig. 6.

It is believed that an understanding of the

operation of the improvements embodying the invention will be had without further detailed description.

This invention is not limited to the details of construction.

I claim as my invention:

1. In a printing press having an automatic stopping device, the combination with a means for feeding the paper sheet to the press, 10 of a pivoted vibrating element having contacting relation with the lateral edge of the paper sheet as it is fed to the press, operative connections between the pivoted vibrating element and the stopping device whereby the press is automatically stopped when the lateral edge of the paper is out of position.

2. In a printing press having automatic stopping mechanism, guide paper shifting 20 mechanism, the combination with a vibrating element intermittently contacting a lateral edge of the sheet fed to the press, of operative connections between the contacting element and the stopping mechanism whereby the interruption of the actuation of the vibratory element will act to cause a stopping of the press when the material is improperly positioned.

3. In a sheet detector for printing presses, 30 having automatic stopping and feeding mechanism, the combination of a detector device comprising a vibrating pivoted lever adapted to contact the paper sheet on one

of its lateral edges, of a spring actuated pivoted lever adapted to lift the contact lever 35 and having an actuating cam acting on the lifting lever, operable connections between the detector device and the stopping mechanism whereby the press is stopped when the sheets are improperly aligned.

4. In a sheet detector for printing presses, having automatic stopping and feeding mechanism, the combination of a detector device comprising a vibratory pivoted lever adapted to contact the lateral edge of the 45 sheet during travel of the sheet, a cam actuated lever operating against spring tension and functioning the vibratory lever, operating connections with the automatic stop whereby failure of contact of the vibratory 50 lever with the sheet will cause stopping of the press.

5. In a sheet detector for printing presses, having automatic stopping and feeding mechanism, the combination of a detector 55 device comprising a vibratory pivoted lever adapted to contact the lateral edge of the sheet, a suspended cam latch and a pivoted lever actuated thereby and functioning the vibratory lever, operating connections between the suspended cam latch and stopping mechanism whereby the failure of the vibratory lever to contact the sheet will produce a 60 stopping of the machine.

HERMAN J. SCHULTZ.
